UNITED STATES PATENT OFFICE

WILLIAM S. HOLDWAY, OF SAWTELLE, CALIFORNIA, ASSIGNOR, BY MESNE ASSIGNMENTS, TO BYRON JACKSON CO., OF WEST BERKELEY, CALIFORNIA, A CORPORATION OF DELAWARE

ROTARY DISK DRILL

Application filed July 20, 1925. Serial No. 44,774.

This invention relates to rotary disk drills such as used in drilling wells. In this type of drill the cutter disks are carried below the end of the shank of the drill, and as usually constructed, each disk is carried upon a fork, the forks being located opposite to each other. In using drills of this type, it has been found that the material cut or excavated by the disks accumulates between the edges of the disks and the end of the shank and frequently becomes clogged at this point. This clogged material sometimes "sets" and becomes so hard that it is very difficult to remove.

The general object of this invention is to provide a rotary disk drill of this type so constructed as to prevent the clogging of material between the disks and the shank; also to provide improved means for insuring that the water supply will be delivered at the face of the disks.

Further objects of the invention will appear hereinafter.

The invention consists in the novel parts and combination of parts to be described hereinafter, all of which contribute to produce an efficient rotary disk drill.

A preferred embodiment of the invention is described in the following specification, while the broad scope of the invention is pointed out in the appended claims.

In the drawings:

Fig. 1 is a side elevation of a rotary disk drill embodying my invention, partially broken away and shown in section.

Fig. 2 is a view similar to Fig. 1 but showing the lower portion of the drill in section.

Fig. 3 is a bottom plan of the drill.

Fig. 4 is a horizontal cross section taken on the line 4—4 of Fig. 1.

In practicing the invention, I prefer to construct a drill with an elongated shank 1, the upper end of which is provided with means such as a threaded tapered pin 2 to be secured to the lower end of the tool string. The lower ends of the two oppositely disposed forks 3 are provided with disks which extend down a considerable distance below the transverse end face 4 of the shank in such a way that a relatively deep

throat 5 is formed between the rotary disks 6 and the end face 4. The disks are mounted opposite to each other and so that the planes of the disks are substantially parallel with each other, though the axes of the disks may be thrown slightly out of alignment with each other (see Fig. 3).

The shank 1 is provided with a water bore 7. In order to take the water from the water bore into the space between the disks 6, and also in order to prevent the formation of clogged material in the throat 5, I provide a separate nozzle 8 which is preferably attached co-axially and of tapered or wedge form in its longitudinal section taken in a plane perpendicular to the axes of rotation of the disks, and this nozzle is provided with a duct 9 which communicates with the bore 7. It is detachably secured by a thread connection. The lower end of this nozzle extends down and projects into the space between the disks, at which point the nozzle delivers the water to the disks.

In order to enable the nozzle 8 to perform its function of expelling the cuttings from the disks, its horizontal cross-section is greater in one direction than the other, and it is preferably constructed so that, as viewed in horizontal cross section (see Fig. 80-4) the longitudinal axis of the cross section extends substantially perpendicular to the planes of the disks. In this way, when the drill rotates the nozzle gives the effect of a central blade rotating in the space between the disks and the end of the shank, and has the effect of pushing the clogged material out of the throat.

The depth of the throat 5 is preferably such that the distance from the edges of the disks to the end of the shank is substantially equal to half the diameter of the disk.

It is understood that the embodiment of the invention described herein is only one of the many embodiments this invention may take, and I do not wish to be limited in the practice of the invention, nor in the claims, to the particular embodiment set forth.

What I claim is:—

1. A rotary disk drill having a shank with forks extending downwardly from the shank and having a transverse end face disposed between the forks and cooperating with the same to form a relatively deep throat between the forks, disk cutters carried respectively by the forks, said shank having a water bore extending through the same, and a separate nozzle detachably secured to the 5 said end face extending down into the throat to a point adjacent the upper edges of the cutters, and having a duct communicating with the water bore and delivering water into the space between the disks, said nozzle 10 being in the form of a tapered blade with a horizontal cross-section greater in one direction than in another, and with its large end seating against the said end face, the space between the nozzle and said forks being left 15 open so that the nozzle operates during the rotation of the drill to expel the material tending to lodge above the level of the disks and between the disks and the said end face.

2. A rotary disk drill having a shank with 20 forks extending downwardly from the shank and with a transverse end face connecting the forks and cooperating with the same to form a relatively deep throat between the forks, disk cutters carried respectively by 25 the forks, said shank having a water bore extending down through the same, and a separate nozzle detachably secured co-axially at the said end face, extending downwardly into the throat and having a duct communicating with the water bore for delivering 30 water into the space between the disks, said nozzle being in the form of a tapered blade whose cross-section has a greater dimension in one direction than in another, and operating 35 to expel cuttings from said disks, there being a space between the sides of the nozzle and the forks, said throat being of such depth that the distance to the end of the shank from the edge of the disks is substantially 40 equal to half the diameter of the disks.

3. A rotary disk drill having a shank with forks extending downwardly from the shank, disk cutters carried respectively by 45 the forks, said shank having a water bore extending down through the same, and a separate nozzle detachably secured to the lower end of the shank extending down into the space between the cutters and having a duct 55 communicating with the water bore and delivering the water to the disks, said nozzle having the form of a tapered blade operating during the rotation of the drill to expel the material between the disks and the end 60 of the shank.

4. A rotary disk drill having a shank with forks extending downwardly from the shank and with a transverse end face connecting the forks, disk cutters carried respectively 65 by the forks, said shank having a water bore

extending down through the same, and a separate nozzle detachably secured to the end face extending down into the space between the cutters and having a duct communicating with the water bore and delivering 70 water to the disks at a point near the upper edges of the disks, said nozzle having the form of a tapered blade, said drill having spaces between the sides of the nozzle and the forks whereby the nozzle operates as a 75 blade during the rotation of the drill to engage and expel material between the disks and the end of the shank.

Signed at Los Angeles, Calif., this 2d day of June, 1925.

WILLIAM S. HOLDAWAY.
